UNITED STATES PATENT OFFICE

2,052,985

PISTON

Adolph L. Nelson, Detroit, Mich., assignor to
 Bohn Aluminum & Brass Corporation, Detroit,
 Mich.

Application December 16, 1927, Serial No. 240,379
 Renewed March 27, 1935

16 Claims. (Cl. 309—13)

This invention relates to pistons, particularly to pistons for use in internal combustion engines, and aims to improve the construction of such pistons.

5 The invention is especially applicable to light weight pistons for automobile engines, and has for an object to provide novel means for carrying thrust loads from the piston pin to the cylinder-bearing portions of the piston. The piston comprises a head having piers extending downwardly to which the skirt is attached, and a particular feature is an offset arrangement of the lower end of the piers where they join the skirt.

10 A further feature of invention resides in providing a construction in which the upper end of the skirt is given a certain amount of flexibility to enable it to ride smoothly over any tight places in the cylinder even when the piston clearance is very small.

15 The parts are so arranged that it is unnecessary to have any slots extending upwardly into the skirt, and the lower end of the skirt forms a continuous annulus.

20 The invention also provides a piston in which the lower end of the skirt is provided with a piston ring and which can be molded in a permanent mold having a three piece core.

25 While preferred embodiments of the invention have been disclosed for purposes of illustration, it should be understood that various changes can be made in the structure without departing from the spirit and scope of the invention as herein-after set forth and claimed.

In the drawings:

30 Fig. 1 is a side elevation of a piston.
 Fig. 2 is an elevation partly in section taken at right angles to Fig. 1.

35 Fig. 3 is an elevation showing a variation.

Fig. 4 is an elevation showing a further variation.

40 Fig. 5 is a side elevation of a piston embodying an additional feature.

Fig. 6 is a bottom plan view of a piston.

45 Fig. 7 is an elevation partly in section of a piston having a ring at its lower end.

Fig. 8 is a section on lines 8—8 of Fig. 7 but with the ring removed and with the core sections in place to illustrate the method of casting.

50 Referring to the drawings for a more particular description of the invention, the reference numeral 10 indicates the head of the piston, while numerals 11 are applied to piers depending from the head and having piston pin bosses 12 formed therein. The skirt comprises an annular portion 55 13 which has a homogeneous connection with

the lower ends of the piers, and cylinder-bearing slippers 14 and 15 which project upwardly from the annulus 13, the slippers being separated from the head by slots 16 and from the piers by vertical openings 17.

5 The head and skirt are formed of any suitable material, such as a light-weight alloy, and in order to control the expansion of the upper ends of the slippers a pair of struts 18 may be placed across the piston connecting the slippers, 10 the struts being formed of some material less expandable than the piston material. These struts prevent excessive expansion of the upper end of the skirt, and in connection therewith it is necessary to form the piston in such a manner that 15 the lower end of the skirt will not expand into harmful contact with the walls of the cylinder in which the piston is operating.

This result may be attained in a variety of ways. For example, in Figs. 1 and 2 I have shown 20 that the skirt may be formed on a slight taper, with the diameter of the lower end of the skirt at A—A slightly less than the diameter at the upper end of the skirt, at B—B.

25 Alternately or additionally the lower end of the skirt may be constructed in such a manner that the diameter C—C parallel to the axis of the pin bosses is less than the diameter D—D, perpendicular to said axis. A convenient method of producing this construction is to grind the lower 30 end of the skirt to an oval or other suitable shape while finish grinding the piston.

35 Either of the arrangements just described provides the annulus 13 with extra clearance below the pin bosses, so that this part of the skirt may expand to a reasonable extent without producing excessive friction in the cylinder.

40 A particular feature of the invention resides in the way in which the annulus 13 is connected with the lower ends of the piers 11. As shown 40 in Fig. 1 these connections 19 are offset from the center line of the pier, and extend up along the sides of the slipper 14 for a considerable distance. This offset arrangement has several 45 advantageous features. For example, in this construction the upper part of the connection 19 approaches the line of thrust from the piston pin to the slipper 14, and by inserting the piston in the cylinder so that the slipper 14 will carry the main thrust load, the connection 19 will 50 help to carry the thrust load and thereby lighten the load on the strut joints. By extending the connection 19 high enough along the slipper 14 it is possible to omit the anchorage at the center 55 of the strut.

If the slipper 15 is slotted upwardly as at 20 in Fig. 4 there results an increased skirt flexibility, while if slipper 14 is slotted as at 21 in Fig. 3, the flexibility is reduced. Thus it will be seen 5 that the degree of flexibility of the skirt is altered by placing the offset pier nearer or farther away from a saw slot in the skirt.

In certain cases it is desirable to give the upper 10 part of the skirt a certain amount of flexibility, and this may be done by cutting a slot or slots downwardly into the skirt as shown at 22 in Fig. 15 5. This construction permits fitting the upper end of the skirt with an unusually small clearance in the cylinder, as the struts control the thermal expansion while the slots permit slight yielding to allow the piston to run by a tight 20 spot in the cylinder without undue friction. This arrangement for making the upper end of the skirt flexible may be used with any type of pier 25 construction, and even without the struts, since the combination of the flexible upper skirt end with solid lower end may be used to produce a piston without struts that will operate satisfactorily.

25 Another feature of the invention resides in making provision for a piston ring at the lower end of the skirt while using a permanent mold having a three-piece core. The wall of the skirt must be kept as thin as possible, and to form 30 a ring groove in the wall necessitates forming a rib on the inside of the skirt to bridge over the groove. But with a three piece core it is impossible to cast ribs in the wall of the skirt abutting the ends of the middle core piece 23 35 since this latter piece must be pulled straight out in order to permit collapsing the side cores 24 toward the center to clear the projecting parts of the wall. The ribs 25 are therefore cast only on the skirt portions facing the core pieces 24, and the ring groove 26 extends into the rib 25 40 and cuts completely through the skirt wall at the points 27 lying between the ends of the ribs 25. A piston ring 28 is accommodated in the ring groove 26.

45 I claim:

1. A piston comprising a head, piers depending from the head and having pin bosses formed therein, an annular portion connected to the lower ends of the piers, tongues extending upwardly from the annular portion and formed of light weight material, and struts of relatively inexpansile material extending across the piston between the tongues, the line of connection between each pier and the annular portion extending partway up along the side of a tongue.

50 2. A piston comprising a head and a skirt formed of light weight material, struts of relatively inexpansile material controlling the expansion of the upper end of the skirt, the skirt being tapered to give the lower end of the skirt a smaller diameter than the upper end thereof when cold.

55 3. A piston comprising a head, piers depending from the head and having pin bosses formed therein, a skirt having an uninterrupted annular portion connected to the lower ends of the piers and tongues extending upwardly from the annular portion, the skirt being tapered to give the lower end of the skirt a smaller diameter than the upper end thereof when cold.

60 4. A piston comprising a head, piers depending from the head and having pin bosses formed therein, a skirt formed of light weight material having an annular portion connected to the lower ends of the piers and tongues extending up-

wardly from the annular portion, struts of relatively inexpansile material controlling the expansion of the upper end of the skirt, the skirt being tapered to give the lower end of the skirt a smaller diameter than the upper end thereof 5 when cold.

5. A piston comprising a head, piers depending from the head and having pin bosses formed therein, a skirt formed of light weight material having an uninterrupted annular portion connected to the lower ends of the piers and tongues extending upwardly from the annular portion, struts of relatively inexpansile material controlling the expansion of the upper end of the skirt, the skirt being tapered to give the lower 15 end of the skirt a smaller diameter than the upper end thereof when cold.

6. A piston comprising a head, piers depending from the head and having pin bosses formed therein, a skirt including bearing portions separated at their upper ends from the head, parts connecting the lower ends of the bearing portions to each other, the head and bearing portions being formed of a relatively light weight material, a pair of struts extending between the bearing 20 portions, the struts being formed of a material having a lower coefficient of thermal expansion than the material of the bearing portions; a pair 25 of webs, each web being homogeneous with a pier and with a bearing portion, the webs extending in a general direction outwardly and downwardly from the pin bosses.

7. A piston comprising a head, piers depending from the head and having pin bosses formed therein, a skirt including bearing portions separated at their upper ends from the head, parts connecting the lower ends of the bearing portions to each other, the head and bearing portions being formed of a relatively light weight material, a pair of struts extending between the bearing 35 portions, the struts being formed of a material having a lower coefficient of thermal expansion than the material of the bearing portions, a pair 40 of webs, each web being homogeneous with a pier and with a bearing portion, the webs extending in a general direction outwardly and downwardly from the pin bosses, the bearing portion adjacent the webs being formed with a slot 45 extending upwardly from the lower edge of the skirt.

8. A piston comprising a head, piers depending from the head and having pin bosses formed therein, a skirt including bearing portions separated at their upper ends from the head, parts connecting the lower ends of the bearing portions 50 to each other, the head and bearing portions being formed of a relatively light weight material, a pair of struts extending between the bearing portions, the struts being formed of a material having a lower coefficient of thermal expansion 55 than the material of the bearing portions, a pair of webs, each web being homogeneous with a pier and with a bearing portion, the webs extending in a general direction outwardly and downwardly from the pin bosses, the bearing portion farthest away from the offset webs being formed with a slot extending upwardly from the lower edge of the skirt.

9. A piston comprising a head, a skirt having pin bosses formed therein, an arcuate rib formed 70 on the inside of the skirt below the piston pin opening in each pin boss, each of said ribs extending circumferentially over a considerable arc of the wall of the skirt, the ribs being discontinued over small arcs at points spaced 90° 75

from the pin bosses, the skirt being formed with a groove extending into said ribs and cutting completely through the skirt along the arcs where the ribs are discontinued.

5 10. A piston comprising a head, a skirt having pin bosses formed therein, an arcuate rib formed on the inside of the skirt below the piston pin opening in each pin boss, each of said ribs extending circumferentially along the skirt wall

10 for at least 90° of the circumference of the skirt, the ribs being discontinued over small arcs on opposite sides of the skirt at points midway between the pin bosses, the skirt being formed with a piston-ring groove extending into said ribs 15 and cutting completely through the skirt along the arcs where the ribs are discontinued.

11. A piston comprising a head, a skirt having pin bosses formed therein, two thrust faces between the pin bosses, the thrust faces lying on 20 opposite sides of the skirt and extending from the top of the skirt to the bottom of the skirt, an arcuate rib formed on the inside of the skirt below the piston pin opening in each pin boss and extending circumferentially along the skirt 25 wall from one thrust face to the other, the ribs being discontinued over small arcs at the circumferential center of each thrust face, the skirt being formed with a groove extending into said ribs and cutting completely through the skirt 30 along the arcs where the ribs are discontinued.

12. A piston comprising a head, piers depending from the head and having pin bosses formed therein, a skirt including bearing portions separated at their upper ends from the head, the 35 head and bearing portions being formed of a relatively light weight material, a pair of struts extending chordally of the piston between the bearing portions, the struts being formed of a material having a lower coefficient of thermal 40 expansion than the material of the bearing portions, each strut having its opposite ends in contact with opposite bearing portions, a pair of webs, each web being homogeneous with a pier and with a bearing portion, the webs extending 45 in a general direction outwardly and downwardly from the pin bosses.

13. A piston comprising a head, a skirt having pin bosses formed therein, arcuate ribs formed on the inside of the skirt, each of said ribs extend-

ing circumferentially along the skirt wall for at least 90° of the circumference of the skirt, the ribs being discontinued over small arcs on opposite sides of the skirt at points midway between the pin bosses, the skirt being formed with a piston-ring groove extending into said ribs and cutting completely through the skirt along the arcs where the ribs are discontinued. 5

14. A piston comprising a head, a skirt having piston pin bosses formed therein, parts of the 10 skirt wall lying adjacent the ends of a diameter at right angles to the axis of the pin bosses constituting thrust faces, the part of the skirt wall lying below the horizontal plane of the axis of the piston pin bosses comprising an annular part, 15 said annular part being formed with a piston ring groove, the piston-ring groove being defined by side walls continuous circumferentially of the piston, and a bottom wall continuous circumferentially around the piston except at the center of 20 each thrust face, where the bottom wall is discontinued and the groove cuts completely through the skirt wall.

15. A piston comprising a head, a skirt having piston pin bosses formed therein, part of the 25 skirt lying below the axis of the piston pin bosses being formed with a piston-ring groove, parts of the skirt projecting inwardly around the groove to form a bottom wall for the groove continuous except at two places adjacent the ends 30 of a diameter perpendicular to the axis of the piston pin bosses, and at said two places there are no parts projecting inwardly from the skirt wall.

16. A piston comprising a head, a skirt having piston pin bosses formed therein, parts of the 35 circumferential wall of the skirt lying between the bosses on each side of the skirt constituting thrust faces, the skirt being formed with a piston-ring groove, parts of the skirt projecting inwardly 40 around the groove to form a bottom wall for the groove, the bottom wall being circumferentially continuous except adjacent the center of each thrust face, where the groove cuts completely 45 through the skirt wall, the center of each thrust face from points adjacent the upper end of the skirt and extending down to the bottom of the skirt, being free of any inwardly projecting parts.

ADOLPH L. NELSON.

DISCLAIMER
